UNITED STATES PATENT OFFICE.

VIRGIL M. HARRIS, OF ST. LOUIS, MISSOURI.

PEN-HOLDER.

SPECIFICATION forming part of Letters Patent No. 365,810, dated July 5, 1887.

Application filed March 1, 1887. Serial No. 229,277. (No model.)

To all whom it may concern:

Be it known that I, VIRGIL M. HARRIS, a citizen of the United States, residing at the city of St. Louis, State of Missouri, have invented a certain new and useful Improvement in Pen-Holders, of which the following is a full, clear, and exact description.

My invention has for its object to obviate the undue constraint and consequent cramping and paralysis of the fingers induced by a continued use of the ordinary pen-holder.

It consists in the application to a pen-holder of two rings embracing, respectively, (in the manner shown in the drawings,) the first and second fingers, between which and the thumb the pen-holder is held and supported by the rings.

On the accompanying drawings, Figure 1 is a side elevation representing my improved pen-holder as held by the hand when writing; Fig. 2, a front view of the pen-holder seen in Fig. 1; and Figs. 3 and 4, front views of modifications thereof, like letters of reference denoting like parts in all the figures.

25 *a* represents a pen-holder, which is preferably made as short as possible, and held by the hand for writing between the ends of the first and second fingers and thumb. From each side of the pen-holder *a*, where it passes 30 between the fingers intermediate to their knuckle and middle joints, projects a ring, *b*, the two rings *b*, through which the first and second fingers are respectively passed, being opposite to and in the same plane with each 35 other and adjusted to such an angle with the center line of the pen-holder *a* that when the

latter is held in the correct position for writing the upper curvatures of the rings *b* will bear lightly upon the upper portions of the first and second fingers near the knuckle-joints 40 and the lower curvatures of the rings *b* against the corresponding portions of the first and second fingers near their middle joints. By this device the undue pressure and constraint hitherto communicated to the ends of the fingers and thumb when using an ordinary pen-holder are relieved and transferred by the rings *b* to the base and strongest parts of the fingers, which are thereby rendered less liable 45 to fatigue and cramp. By its use also a readier 50 means of holding the pen-holder *a* is afforded and the operation of the pen facilitated.

The rings *b* may be made of wire passed through and secured in or affixed to the pen-holder *a*, as shown in Figs. 1 and 2; or they 55 may be made of wood, gutta-percha, rubber, metal, or other suitable material in one with the pen-holder *a'*, as seen in Fig. 3.

It is obvious that my invention is equally applicable to a lead-pencil. 60

I claim as my invention—
The combination, with a pen-holder, of rings *b*, being opposite to and in the same plane with each other, substantially as shown, and for the purpose described. 65

In testimony whereof I affix my signature, in presence of two witnesses, this 26th day of February, 1887.

VIRGIL M. HARRIS.
